(57) **CLAIM**

The ornamental design for a paint spray gun cup, as shown and described.

DESCRIPTION

FIG. 1 is a top view of a paint spray gun cup according to the present invention;

FIG. 2 is a bottom view of the paint spray gun cup of FIG. 1; FIG. 3 is a side view of the paint spray gun cup of FIG. 1, with all other side view orientations being identical; and, FIG. 4 is a perspective view of the paint spray gun cup of FIG. 1.

The broken line showing is included for the purpose of illustrating and forms no part of the claimed design.
